NUCLEAR ELECTRICAL GENERATOR

Ernest G. Linder, Princeton, N. J., assignor to
 Radio Corporation of America, a corporation
 of Delaware

Application August 3, 1951, Serial No. 240,211

7 Claims. (Cl. 310—3)

1

This invention relates generally to the generation of electrical energy and particularly to improved methods of and means for deriving and utilizing the electrical energy of nuclear reactions.

The enormous magnitudes of energy provided by certain nuclear reactions of radioactive substances provide a tremendous field for the development of new sources of electrical energy. Since some radioactive radiations (energy) are largely electrical in nature, it is desirable that such electrical energy be converted directly to electrical energy of usable form. The alpha-particle and beta-particle emissions from certain radioactive substances comprise positively or negatively charged particle rays, respectively having energies which vary from low values to several million electron volts. For example, alpha-ray emission comprises positively charged particles having energies varying from zero to the order of ten million electron volts, while beta-particle emission comprises negatively charged particles having energies varying from low values to the order of three million electron volts. Different radioactive substances are known to provide either alpha-particle emission, beta-particle emission, or a combination of alpha-particle and beta-particle emission. The direct utilization of the high electrical potentials which may be derived from such charged particles provides much more convenient and efficient utilization of nuclear energy than previously proposed systems wherein the nuclear energy is converted to thermal energy, the thermal energy converted to mechanical energy, and the mechanical energy then converted to electrical energy in a usable form. Also the direct utilization of the electrical energy of nuclear reactions may be much more readily controlled by electrical methods than may the conversion of nuclear energy to thermal energy.

The instant invention is an improvement over the devices disclosed in applicant's U. S. Patent 2,517,120, filed June 25, 1946, granted August 1, 1950. Said patent discloses the use of collector electrodes for collecting the charged particle rays from a radioactive source, and means for applying the resultant unidirectional potential between the source and collector electrodes to a load.

One of the factors which greatly limits the efficiency of all radioactive generators is the absorption within the radioactive material itself of particles emitted from the interior thereof.

The instant invention utilizes improved emitting

2

and collecting structures comprising substantially equi-spaced sheet-like emitting and collecting electrodes separated by charged particle permeable insulating means which support the elements in said equi-spaced relation.

A first embodiment of the invention employs a plurality of alternately arranged emitting and collecting sheet electrodes separated by suitable insulating spacers, the several emitters and collectors being respectively connected in parallel to common load terminals, the entire assembly being supported within an evacuated enclosure.

A second embodiment of the invention employs a structure similar to the first embodiment with the exception that the emitting and collecting electrodes are effectively connected in series to provide an output voltage dependent upon the number of series-connected sections.

A third embodiment of the invention employs a pair of emitting and collecting sheet electrodes arranged in a spiral, the adjacent electrode portions being separated by suitable insulating spacers. The latter structure has the advantage that relatively large active surface areas may be incorporated in a compact unit.

One of the objects of the invention is to provide improved and more efficient methods of and means for generating electrical energy in response to nuclear reactions.

Another object is to provide improved and more efficient electrode structural arrangements for utilizing the electrical energy in nuclear reactions for generating high unidirectional potentials.

An additional object is to minimize the internal absorption of radioactive emission in the emitter material of nuclear generators.

A further object is to provide improved means for converting atomic energy directly to electrical energy in commercially usable forms.

The various embodiments and features of the invention will be described in greater detail hereinafter by reference to the accompanying drawing of which Fig. 1 is a schematic diagram of a first embodiment of the invention having a plurality of emitters and collectors connected in parallel; Fig. 2 is a schematic diagram of a second embodiment of the invention having a plurality of emitters and collectors connected in series; and Fig. 3 is a schematic diagram of a third embodiment of the invention having the collectors and emitters in a spiral arrangement. Similar reference characters are applied to similar elements throughout the drawings.

Before describing the detailed structure of the

several embodiments of the invention, the general characteristics of radioactive voltage sources will be described briefly. Known beta-ray emitters provide electrons having energies from almost zero to 3 million electron volts. Known alpha-ray emitters provide positively-charged alpha-particles having energies from about zero to the order of 10 million electron volts. If desired, an alpha-particle source may be employed instead of a beta-particle source, in which case the collector electrode will be charged positively until it reaches a potential sufficiently high to repel additional alpha particles. In such a modification of the invention, the collector electrode becomes the positive terminal and the radioactive source the negative terminal of the generator.

The electric current produced by any source of charged particles is

$$(1) \quad i = e \frac{dn}{dt}$$

where n is the number of particles emitted, t is the time in seconds, and therefore dn/dt is the rate of particle emission, and e is the electrical charge per particle. If each particle carries more than one electronic charge, e must be replaced by μe , where μ is the number of charges.

For a radioactive substance

$$(2) \quad dn/dt = -\lambda n$$

(see Pollard and Davidson, Applied Nuclear Physics, p. 105), where λ is the decay constant and is related to the half life t_H by

$$(3) \quad \lambda = \frac{0.693}{t_H}$$

From Equations 1, 2 and 3 it is seen that

$$(4) \quad i = \mu e n \frac{0.693}{t_H}$$

The number of atoms contained in a substance of mass M and atomic weight A is

$$(5) \quad n = \frac{M}{m_H A}$$

where m_H is the mass of the hydrogen atom. Thus

$$(6) \quad i = \mu e \frac{0.693 M e}{m_H A t_H}$$

This relation may be expressed in amperes per gram for a predetermined quantity of a radioactive substance wherein $e=1.59 \times 10^{-19}$ coulombs, $M=1$ gram, $m_H=1.66 \times 10^{-24}$ grams, and $t_H=8.64 \times 10^4 T_H$, where T_H is the half life in days. Therefore,

$$(7) \quad i_i = \frac{0.76 \mu}{A T_H}$$

If the radioactive source is polonium, $A=210$ and $T_H=140$, $\mu=2$, therefore

$$(8) \quad i_i = \frac{0.76 \times 2}{210 \times 140} = 51.8 \times 10^{-6} \text{ amps./gram}$$

$$= 51.8 \text{ microamps./gram}$$

The characteristics of the charged particle emitting substance determine not only the output voltage of the generator, but also determine its impedance. Thus, since alpha particles generally have very uniform energy providing the source is a very thin element, the generated voltage would remain substantially constant until all the remaining current was drawn, whereupon the voltage would decrease rapidly. Thus, with

an alpha-particle emitter, the generator would have a low effective internal impedance. In contradistinction thereto, beta particles are usually emitted over a wide energy range which may vary from a very low value to several million electron volts. Consequently, when current is drawn from the generator to a load, the load voltage would immediately drop to a much lower value than the no load maximum, as is characteristic of all generators having high internal impedance. The actual variation of load voltage with current would depend upon the particular characteristics of the beta-ray emitting material. In general the available power depends upon the quantity of radioactive material employed and upon its rate of particle emission. Materials which emit at high rates have short operating life, while materials emitting at low rates have relatively longer operating lives. In general, generators of the types described have particular application for systems requiring high voltage and low power capacity since in such instances only a relatively small amount of radioactive material is required for the alpha- or beta-ray source.

Following is a partial list of alpha- and beta-ray emitters which are suitable for high voltage generators of the types described heretofore:

ALPHA-RAY EMITTERS

Element	Half-life, days	Energy (equivalent million electron volts)
Polonium (Po 210)	140	5.30
Actinium (Ac 223)	11.2	6.72
Thorium, X (Th X 224)	3.64	5.68
Radio actinium (Rd Ac 227)	13.5	5.00

BETA-RAY EMITTERS

Phosphorus (P 32)	14.30	1.72
Calcium (Ca 45)	180	0.26
Scandium (Sc 45)	85	0.36
Iron (Fe 59)	47	0.26
		0.46
Arsenic (As 75)	16	1.3
Strontium (Sr 89)	54	1.5
Strontium (Sr 90)	125	0.60
Antimony (Sb 124)	60	2.4
Cerium (Ce 144)	275	0.35
Tungsten (W 185)	77	0.675

¹ Years.

Referring to Fig. 1 of the drawing, the first embodiment of the invention includes a plurality of radioactive emitters 1 cooperating with a plurality of emission collecting electrodes 3 and spaced therefrom by a plurality of charged particle permeable, such as open mesh, insulators 5 all enclosed within an evacuated enclosure 7. All of the emitters 1 are connected together and brought out through the evacuated enclosure through an output lead 9. Similarly, all of the collectors are collected together and brought out through a second output lead 11. The output leads 9 and 11 are connected to any desired load 13.

The radioactive emitter 1 may comprise, for example, aluminum foil of the order of .002 inch in thickness coated with the desired radioactive emitter such, for example, as strontium 90 oxide. Alternatively, the emitters may comprise a double layer of thin aluminum foil or other substantially radiation-permeable conducting material having the radioactive emitting substance disposed in a thin layer between the layers of foil.

The collecting electrodes 3 preferably are of

conducting material sufficiently thick to stop substantially all alpha-ray or beta-ray radiation, as the case may be. Electrodes of 3 millimeter thick iron would be suitable. The open mesh insulator may comprise a polystyrene mesh of sufficient thickness to provide the desired spacing and insulation breakdown characteristics between the emitters and the collectors. The appropriate spacing provided by the insulating meshes 5 will depend upon the load impedance which will determine the average output voltage. Since a plurality of relatively large area emitters and collectors are relatively connected in parallel, the output current derived from the embodiment shown in Fig. 1 may be as much as one thousand times greater than would be obtainable from the same quantity of radioactive emissive material concentrated in a compact volume as described in applicant's patent identified heretofore.

The second embodiment of the invention shown in Fig. 2 utilizes a plurality of series-connected emitters and collectors providing a much higher output load voltage with correspondingly lower maximum load current. In this embodiment of the invention the emissive material 1 is coated upon one surface of the relatively heavy collector electrodes 3. The radioactive emission from each emitter 1 is collected upon the adjacently disposed surface of the next collector electrode 3 which is spaced from the first emitter by a mesh insulator 5 as described heretofore. Thus the voltage generated between successive emitters and collectors is additively combined to provide an extremely high output load voltage.

In both of the embodiments of the invention illustrated in Figs. 1 and 2, the relatively thick absorbing collector electrodes prevent interaction between the several emitting electrodes which would tend to discharge the device internally.

A particularly efficient and compact modification of the first embodiment of the invention is shown in Fig. 3. This device comprises a thin foil of aluminum or other conducting material having radioactive emissive material coated in a thin layer on both surfaces thereof. Alternatively, the radioactive material may comprise a thin layer disposed between two extremely thin conducting foils as described heretofore in Fig. 1. An adjacently disposed, relatively thick, emission-absorbing collector 5 having the same, or slightly larger, area as the emissive electrode is separated therefrom by a suitably proportioned mesh insulator 5. The whole assembly is formed into a spiral cylinder and enclosed within an evacuated envelope, not shown. Thus the radioactive emitter 1 radiates charged particles which are collected on both sides of the emitting structure by the adjacently disposed turns of the heavy absorbing collector 3. The device thus provides relatively large output currents from a predetermined quantity of radioactive emissive material. Support of the relative spacing of the emitter and collector is facilitated by the spiral conformation of the elements.

Thus the invention described comprises more efficient utilization of charged particle emission from radioactive emitting sources for the direct generation of electrical energy at high voltage and relatively low current.

What is claimed is:

1. Apparatus for primarily generating electrical energy including an evacuated envelope containing a plurality of emitters comprising radioactive material providing charged particle cold high energy emission, a plurality of collector electrodes alternately interspersed between and closely juxtaposed with said emitters, said emitters and collector electrodes comprising effectively equi-spaced sheet-like elements, insulating means substantially permeable to said emission for supporting said elements in said equi-spaced relation, and means connected to said elements for deriving a load current.
- 15 2. Apparatus according to claim 1 wherein said emission from each of said emitters is collected on one of said collector electrodes.
- 20 3. Apparatus according to claim 1 wherein said emission from each of said emitters is collected by a plurality of said collector electrodes.
- 25 4. Apparatus according to claim 1 wherein said collector electrodes are substantially opaque to said emission.
- 30 5. Apparatus for primarily generating electrical energy including an evacuated envelope containing a plurality of emitters comprising radioactive material providing charged particle cold high energy emission, a plurality of collector electrodes alternately interspersed between and closely juxtaposed with said emitters, said emitters and collector electrodes comprising effectively equi-spaced sheet-like elements, insulating means substantially permeable to said emission for supporting said elements in said equi-spaced relation, and separate means respectively shunt connected to said emitters and to said collector electrodes for deriving a load current.
- 35 6. Apparatus for primarily generating electrical energy including an evacuated envelope containing a plurality of emitters comprising radioactive material providing charged particle cold high energy emission, a plurality of collector electrodes alternately closely interspersed between and closely juxtaposed with said emitters, said emitters and collector electrodes comprising effectively equi-spaced sheet-like elements for establishing incremental potentials, insulating means substantially permeable to said emission for supporting said elements in said equi-spaced relation, and means connected to said elements for combining said incremental potentials for deriving a load current.
- 40 7. Apparatus according to claim 6 wherein each emitter comprises radioactive material disposed upon a single face of one of said collector electrodes, said emitter being insulated from the next adjacent one of said collector electrodes.
